UNITED STATES PATENT OFFICE

MILTON ALDEN, OF SPRINGFIELD, MASSACHUSETTS, ASSIGNOR, BY MESNE ASSIGNMENTS, TO RADIO INVENTIONS, INC., A CORPORATION OF NEW YORK

CONVERTER

Application filed January 26, 1928. Serial No. 249,635.

My invention relates particularly to radio receiving apparatus and the main object is to provide a simple form of device for conversion of radio receivers designed to operate with vacuum tubes whose cathodes are heated by direct current to a type of receiver employing the more modern vacuum tubes whose cathodes are operated either directly or indirectly from an alternating current source, without structural or wiring changes in the receiver proper.

Another object is to facilitate insertion of the prongs of the tube into the device.

Another object is to so design the parts that they may be employed in various combinations for use under different circumstances.

Another object is to provide an adaptor or converter of this character which is compact and yet will provide a large area of contact required by the alternating current cathode tube and also will not greatly increase the head-room taken by the tubes and sockets.

Another object is to make easy the use of the so-called "central point connection" generally employed with tubes whose cathodes are directly heated by alternating current without disturbing the internal structure or wiring of the existing receiver.

An additional object is to provide in the same device an adjustable means for varying the regeneration in the radio frequency circuits of such a receiver when the alternating current type of tube is employed.

Another object is to provide a device into which an additional resistance may be readily inserted in one line without the use of tools or binding posts and without disturbing the receiver.

I have shown the invention embodied in three combinations. In each case the device comprises a base suitable for insertion in standard vacuum tube sockets. This base carries the standard contact pins or prongs and is provided internally with contacts to be engaged by the prongs or pins of what are commonly termed A. C. tubes. The device also has a top member provided with passages for the A. C. tube prongs. One or

more of the interior contact members are provided with conducting extensions which extend between the interfitting edges of the top and base and are themselves provided with suitable means for connection to conductors.

Fig. 1 is a side view of one form of converter embodying my invention and shows means for alternating current filament connection, and central point connection to the filament wiring of the adapted receiver.

Fig. 1a is a diagram showing one way in which the device of Fig. 1 can be connected in circuit.

Fig. 2 is a plan view of the device of Fig. 1 with condensers and resistors attached.

Fig. 3 is a sectional view on the plane of the line 3-3 of Fig. 2.

Fig. 4 is a plan view of the base member with its contacts and projecting conductor terminal for central point connection.

Fig. 5 shows the inside of the top member.

Fig. 6 is a vertical sectional view of another form of the invention provided with a removable grid damping resistor.

Fig. 7 is a plan view of the base member of Fig. 6 with some of the contacts removed.

Fig. 8 is a perspective view of the grid resistor.

Fig. 9 is a perspective view of the parts of the resistor.

Fig. 10 is a perspective view of one of the removable contacts having an extension terminal.

Fig. 11 is a vertical sectional view of another modification.

The base 15 is preferably formed of insulating material and has prongs such as 16 and 17 corresponding to the usual prongs of a vacuum tube in size and location.

The top member 18 is also preferably formed of insulating material and provided with passages such as 19 and 20 corresponding in size and location with the prongs of an alternating current tube. These two members are preferably provided with flanges 21 and 22 respectively which overlap each other and provide an enclosed chamber or chambers for the contact members. The device is adapted to be inserted into sockets of

55

60

65

85

90

100

the push-pull type and is also preferably provided with a projecting pin 23 adapted to be used in a bayonet type socket. The two parts of the body are preferably secured together by a tubular rivet 24.

In the form shown on sheet 1 the contacts 25 and 26 are provided with spring tips which are inclined so as to be frictionally and resiliently engaged by tube prongs inserted through the top passages, these two contacts having their feet bent inwardly and secured to the base by rivetting over the inner ends of corresponding prongs as shown in Fig. 3.

Two other contact members similar to that illustrated in Fig. 10 are provided, each of which has an inclined spring tip 27, an inclined spring arm 28, and an extension 29 provided with a binding post or nut 30. This member is held in place between the overlapping flanges of the top and base members of the body. The top is also provided with interior pairs of lugs such as 31 and 32 which serve to laterally position or retain in position the interior spring contacts.

A central point connecting member 33 is provided with a T-shaped foot 34 (Fig. 4) the ends of which are electrically connected with the large prongs 17. This T-shaped foot is covered with insulating material 35 so as to prevent accidental electrical contact between the foot and the immediately adjacent contact members.

The top member is preferably provided with a groove 36 which provides inner and outer annular shoulders 37 and 38 for accurately guiding the prongs of a tube to be inserted. This greatly facilitates the insertion of the tube in the proper position. This element is of considerable importance in modern radio set construction because of the compact arrangement of the parts of the apparatus which makes it difficult not only to see where the prong openings are but even too difficult to find the openings. The walls of these grooves are preferably colored according to some prearranged code for instance—green for a five prong tube—orange for a power tube, and red for other tubes, in fact these rings may be painted with phosphorescent or other luminous paint so as to facilitate finding the entrance to the sockets even in the dark.

Fig. 1a shows the circuit arrangement for a converter such as above described being adapted for central point connection and suitable grid bias. The resistances 40 and 41 are of equal value and of the order of 50 ohms. The resistor 42 is of the order of 1000 ohms while the condensers 43 and 44 have preferably a value of as large or larger than 0.1 mf. The filament 45 of the tube to be inserted in the device of Fig. 1, sheet 1, and having its terminals connected to the contacts of extensions 29 and 29'. The prongs 17 of the converter are connected as

above described to the T-shaped foot 34 of the extension 33 to which one end of the resistor 42 is connected. The other end of the resistor 42 is connected midway between the resistors 40 and 41 whose other terminals are connected to the tube prong contacts 29 and 29'. The condensers 43 and 44 are connected between the outer terminals of the resistors 40 and 41 and the common terminal plate 34 of the prong 17. The resistors 40, 41 and 42 may be all wound on an insulating segment adapted to be supported by the extension conductors 29, 29' and 33. The condensers 43 and 44 may also be conveniently supported from the said extensions as shown in Fig. 2.

Figs. 6 and 7 show a converter which is adapted to control regeneration in radio frequency amplifying stages by the insertion of resistors of various values between the grid and its associated tuned circuit. Its general construction is similar to the device shown on sheet 1 except for certain additional features and the omission of the connector 33.

The top portion 18' is provided with an aperture 50. Directly below this aperture is the contact 51 which is connected to the pin 52 which normally engages the grid contact of the set socket (not shown). The inner side of the spring contact 53 receives the grid pin of the vacuum tube (not shown). The foot of the contact 53 is insulated from the pin 52 by the insulation 55. Between the contacts 51 and 53 may be inserted the resistor 54 through the aperture 50. If the grid resistor 54 is not desired it may be removed in which case the contacts 51 and 53 engage each other thus directly closing the grid circuit. Connection to the plate of the tube is made by the contact 56 and two spring contacts such as 27 are provided for leading the alternating current to the filament.

The resistor 54 may be constructed as shown in Figs. 8 and 9. 60 is a piece of insulating material on which is wound the resistance wire 61 having terminals 62 and 63. On either side of the form 60 is placed an insulating piece 64 and against these pieces are placed the metal parts 65 each having a single lug 66 on one extremity and a pair of lugs 67 on the other extremity. These lugs are bent over as shown in Fig. 8 to hold the parts together and the lugs 66 engage the bare ends 62 and 63 of the resistance wire and contact therewith so that each metal plate forms a terminal for the resistor.

These resistors can be made in various values to meet the requirements of differing receivers.

Fig. 11 shows a simpler form of converter in which the filament prongs 17 of the converter are isolated from the filament prongs of the tube which later engage contacts such as 27 having terminals 29, and the grid and plate prongs of the converter have attached

to them contacts such as 26 which receive the grid and plate prongs of the tube (not shown).

It will be seen from the drawings that my 5 construction provides a long and firm contact of large area which is a matter of great importance when using the present alternating current tubes as the cathodes of these tubes draw several times the current employed by 10 equivalent direct current tubes.

The inclined spring contacts 26 and 27 are preferably so designed as to normally bear on the tapered or inclined part 18' of the top member. When the tube prongs are inserted the tips 26 and 27 bend outwardly so as to afford a maximum perfection of contact. The contacts bend not only at the tips, but along their whole lengths. The mid-tap resistance might be wound directly about the 20 side wall of the top member.

Certain features of the invention are also applicable to devices for connecting five prong tubes into four contact sockets and also for connecting four prong tubes into five hole 25 sockets.

The construction shown in Figs. 6 and 7 herein including the two contact members 51 and 53 which normally engage one another but which are adapted to be separated by the 30 insertion of a device through the slot 50, is claimed in my divisional application 499,957, filed December 4, 1930.

I claim:

1. A connecting device comprising an insulating base, contact prongs projecting from one end of said base, spring contacts mounted within said base, some of said spring contacts being electrically connected to some of said prongs, a number of conductor terminals extending upwardly from said base in the opposite direction from said prongs and having spring contact portions within said base, a top member telescoping said base and having passages in line with said spring contact members and a central rivet for securing the top member and base together.

2. A tube connecting device, comprising an insulating base and an insulating top, said members having interfitting flanges, projecting prongs secured to said base, said top having passages for similar prongs, spring contacts enclosed by said members some of said contacts being connected to said prongs, and conductor terminals connected to others 55 of said contacts and extending outwardly between the interfitting flanges of the top and base member and provided with external circuit terminals.

3. A tube connector comprising an insulating base having projecting prongs and an insulating top having passages in line with said prongs, spring contacts mounted between said members and connected to some of said prongs and other contacts mounted 65 between said members and having projecting

conductor terminals laterally of said base and current modifying means supported by said terminals outside the base.

4. An adapter for the conversion of a vacuum tube radio receiver from the use of a direct current cathode heating source to the use of an alternating current cathode heating source, said adapter having prongs like and registering with those of a direct current tube and apertures and contacts registering with those of an alternating current tube, means for isolating the adapter prongs from the filament circuit of said receiver, means for giving electrical access to the filament for an alternating current cathode heating source, and means for giving electrical access to a point corresponding to the center of emission of said cathode.

5. A connecting device comprising an insulating base, contact prongs projecting from one end of said base, spring contacts mounted within said base, some of said spring contacts being electrically connected to some of said prongs, a number of conductor terminals extending from said base in the opposite direction from said prongs and having spring contact portions within said base, a top member secured to said base and having passages in line with said spring contact members, and a bayonet lock pin in the side wall of said body so that said connector is adapted for use in both the shell type and push type of socket.

6. A tube connector comprising an insulating base having passages for tube prongs and having an internal conical wall intersecting said passages and contact members mounted in said base having spring arms of inverted V-shape, the inner ends of said arms being inclined across the inner ends of said passages and bearing against said conical wall, some of said contact members having terminal portions extending outwardly from the edge of said base for circuit connection.

7. A radio set connector comprising an insulating base having projecting prongs for insertion into the socket of a direct current set, contacts mounted within said base, two of which are connected to two of said prongs, external terminals extending from an edge of said base and connected to other contacts in said base, and a third external terminal projecting from an edge of said base and connected inside the base to two of the prongs, said base having passages for the insertion of tube pins to said contacts.

8. A radio set connector comprising an insulating base having projecting prongs for insertion into the socket of a direct current set, contacts mounted within said base, two of which are connected to two of said prongs, external terminals extending from an edge of said base and connected to the other contacts in said base, and a third external terminal projecting from an edge of said base

- and connected to two of the prongs, said base having passages for the insertion of tube pins to said contacts, and a resistance supported from some of said terminals and connected between the same.
9. A connector having an insulating base provided with two large and two small contact prongs, a forked connector having an upward and outward extension terminal attached to said large prongs, two contact members for engaging the prongs of a vacuum tube attached to said two small prongs, two contact members for engaging the prongs of a vacuum tube having upward and outward extension terminals and means for mounting resistance and capacity units upon said extension terminals.
10. A connector having an insulating body, socket engaging prongs on said body, said body having apertures adapted to register with the terminals of a vacuum tube, contact members attached to some of said prongs in the body and adapted to receive the terminals of a vacuum tube, an upwardly extending lead member attached to two others of said prongs in the body, upwardly extending lead members having at their lower ends contacts in said body adapted to receive the terminals of a vacuum tube, and means supported by said lead members for obtaining electrical access to the center of the filament of said vacuum tube.
11. A radio set connector comprising an insulating base having projecting prongs for insertion into the socket of a direct current set, contacts mounted within said base, two of which are connected to two of said prongs, external terminals extending from an edge of said base and connected to the other contacts in said base, and a third external terminal projecting from an edge of said base and connected to two of the prongs, and resistance and capacity elements supported from said terminals and connected between the same.
12. A radio set connector comprising an insulating base having projecting prongs for insertion into the socket of a direct current set, contacts mounted within said base, two of which are connected to two of said prongs, external terminals extending from an edge of said base and connected to other contacts in said base, and a third external terminal projecting from an edge of said base and connected to two of the prongs in said base, and means supported by said external terminals for adapting the set to alternating current cathode heating supply.
13. A tube connector comprising an insulating base having passages for tube prongs and having an internal conical wall intersecting said passages and contact members mounted in said base having spring arms of inverted V-shape, the inner ends of said arms being inclined across the inner ends of said passages and bearing against said conical wall, some of said contact members being riveted to some of said prongs said base having a recess for the free action of the outer parts of the spring arms.
14. A connector comprising a base having projecting prongs, a top having passages, a contact connected to at least one prong inside said base and in line with one passage and a conducting strip having an external binding post and having a portion clamped between the top and base and having an inverted V-shaped spring contact portion integral with the strip and in line with another passage and means for securing the top and base together.
15. A connector comprising an insulating base having four projecting prongs, contacts connected to two of said prongs, respectively, a plate connecting the other two prongs, a conducting strip connected to said plate and extending outside of said base, two other contacts mounted in the base above but insulated from said plate and a top member having passages in line with all of said contacts.
16. A vacuum tube connector comprising a cup-like base having contact prongs projecting from its lower face and having a peripheral flange, a contact secured to the upper end of at least one of said prongs, a connecting strip connected to at least one other of said prongs and an insulating top member telescoping with the flange of said base and having a passage for the contact pin of a tube in line with said contact, said strip extending upwardly between said flange and the margin of said top member and having an external means for circuit connection.
17. An electrical connector comprising insulating base and top members having overlapping flanges with a space between the flanges, terminal prongs projecting from the base member, contacts connected to some of said prongs within the top member, a connector strip having a spring contact tip in said space, an external terminal and a connecting member held in place by the flange of said top member, said top member having passages permitting the insertion of prongs into engagement with said contacts and said contact tip.
18. An electrical connector comprising an insulating base, a number of contacts mounted on said base, an insulating top adapted to be secured to the base and having four cylindrical passages permitting the insertion of tube prongs to engage said contacts, said top having a positioning and identifying groove in its outer face intersecting the outer ends of said passages and colored to indicate the type of tube to be inserted in the device according to a predetermined code and means for external connection between the base and top to one of said contacts.

19. An electrical connector comprising an insulating base having a circuit terminal and a peripheral flange, an insulating top having a peripheral flange spaced apart from the first mentioned flange, said top having passages for the insertion of tube prongs and said top having projecting lugs on its inner wall adjacent one of said passages and a connecting strip having a portion located between said flanges, a contact portion in line with one of said passages, and a resilient connecting arm positioned between said lugs.
20. An electrical connector comprising two parts having overlapping flanges, one part having a number of prongs projecting from its outer face and having spring contacts some of which are connected to prongs, the other part having passages in line with the spring contacts and a connecting strip clamped between said flanges and having its inner end connected to one of said contacts between said parts and having a circuit terminal on its outer end.
